SURFACE CLEANING AND SHAMPOOING
MACHINE

Edward Berberian, Union City, N. J.

Application November 24, 1947, Serial No. 787,737

2 Claims. (Cl. 15—321)

1

This invention relates to improvements in surface cleaning and shampooing machines such as shown and described in my earlier application Serial Number 633,162, filed December 6, 1945.

In accordance with the invention of my said earlier application, a pair of squeegee elements, each composed of a substantially arcuate perimetric portion and a radial portion, are so mounted upon the bottom surface of a rotatable head that the arcuate perimetric portions of the two members extend continuously around the perimeter of the head to prevent the escape outwardly of cleaning liquid fed to a surface to be cleaned below and within the perimeter of the head, and each of said pair of squeegee elements has a radial portion continuous with and extending inwardly from its perimetric portion and terminating adjacent to the axis of the head so as to engage and lead spent cleaning fluid, fed as above stated, toward the center of the head where a suction pipe is located for the purpose of sucking the same by vacuum upwardly through the head into a tank. All said squeegee portions have a rubbing contact with the surface to be cleaned and each radial portion is provided with a concave section facing in the direction of rotation for the purpose of guiding such spent liquid to the center, as aforesaid. Said radial squeegee portions are positioned to provide boundaries of areas of the circular head in which scrubbing brushes are mounted, so that upon rotation of the head, the brushes will scrub the surface beneath said head with said cleaning liquid fed as aforesaid, the perimetric squeegee portions will prevent the cleaning liquid from moving centrifugally during rotation of the head and escaping outwardly from beneath said head and the radial portions will guide the liquid toward the center as aforesaid. My said application also discloses a vacuum hose or pipe, which extends from a suitable vacuum tank to the forward end of the machine, with an axially-located portion passing through the head and having an entrance opening centrally located below the under surface of the head to suck up spent liquid which is then conducted to said vacuum tank.

Claims are being made in said copending application for the above subject-matter, particularly covering a rotatable head having a squeegee provided with a perimetric portion and a radial portion with concave sections facing in the direction of rotation and extending outwardly from the axis of the head in the direction of rotation to a head-encircling perimetric portion to guide and deflect cleaning material used on the surface of a rug to a collection place beneath the bottom surface of the head, together with means for removing the material at the axis, and being claimed in my said copending application, are not broadly claimed herein. One of the objects of my present

2

invention is to provide in a machine of the character specified a novel and improved squeegee guiding element having a guiding portion for spent or used cleaning liquid that will greatly facilitate the guided movement of such spent liquid toward and to the center of the head, will reduce the resistance thereof against such movement to a removal point at the center or axis of the head, and will enable a more uniform and efficient distribution of the brushes by and through which part of the cleaning material will be carried in the scrubbing operation thereof, and will cause such brushes more fully to cooperate with the squeegee in the guiding and carrying toward the axis of the apparatus of the spent liquid cleaning material.

Another object of my present invention is to re-reduce the cost of the head by a simplifying arrangement of the liquid-guiding squeegee portion and the scrubbing brushes in relation thereto.

Still another object of my invention is to provide a head-construction in which head-mounting and motion transmission mechanism is greatly simplified and lightened and the platform and sprocket-and-chain arrangement of my former machine are eliminated.

Still another object of my invention is in a device of the character specified to provide an improved gear arrangement and mechanism for transmitting motion from the motor to the revolving head.

Another object of my invention is in a device of the character specified to provide a vacuum pipe which is necessarily located at the axis of the head for sucking up spent cleaning materials, to provide in fixed position on the head a driven ring gear coaxial with and surrounding said pipe, and to utilize a supporting casing having a motor mounted therein with its shaft arranged coaxially of said pipe; to provide a centrally-located drive gear on the motor-shaft and transmission gears mounted upon shafts positioned in said frame radially of said axis and adapted to rotate said ring gear, and I preferably utilize a plurality of radially-positioned shafts and transmission gears to drive said driven ring gear and head, thus eliminating the platform and the sprocket-and-chain arrangements of my former construction and providing a symmetrical construction and arrangement of parts in which weight is uniformly distributed.

Still another object of my invention is to provide a construction in which the vacuum hose will be extended from the same end of the machine as the operating handle so as to avoid obstructions on the outer edge of the machine and to permit the head to be moved closer to walls, partitions and other similar movement-limiting obstructions.

With these and other objects in view, the inven-

tion comprises the combination of members and arrangement of parts so combined as to co-act and cooperate with each other in the performance of the functions and the accomplishment of the results herein contemplated, and comprises in one of its adaptations the species or preferred form illustrated in the accompanying drawings, in which:

Fig. 1 is a view in side elevation of apparatus embodying my invention;

Fig. 2 is a view in plan of the apparatus shown in Fig. 1;

Fig. 3 is an enlarged view partly in elevation and partly in section of the top portion of the vacuum tank shown in Figs. 1 and 2;

Fig. 4 is a view, partly broken away, showing in vertical section substantially through the center of my revolving head with squeegee and brushes and also the mounting frame and adjacent parts.

Fig. 5 is a bottom plan view of the apparatus shown in Fig. 4;

Fig. 6 is a vertical section on the line 6—6 of Fig. 4, looking in the direction of the arrow; and

Fig. 7 is an enlarged fragmentary vertical section of an edge portion of the revolving head with a modified form of squeegee.

In accordance with my present invention, I utilize a circular head and provide on the bottom surface thereof a squeegee element composed of a circular perimetric portion extending completely and continuously around the perimeter of the head and an inwardly-directed liquid guiding portion of general spiral conformation and connected at its outer end to the perimetric portion, having its concave face extending in the direction of rotation and being disposed to extend in a spiral path completely around the axis of the head, and to terminate at said axis in adjacency to a suction tube arranged coaxially with said head. Said inwardly-directed portion of the squeegee provides an area between the outer surface thereof and the perimetric portion and also between inwardly disposed surfaces of itself an area of substantially spiral conformation within which said brush is located.

Referring now to these drawings, which illustrate preferred embodiments of my invention, 10 indicates a circular head which is mounted in a partly cylindrical and partly frusto-conical gear-enclosing casing 11 to revolve beneath said casing, which is preferably composed of cast metal, and supports at its axis a vertical section 12 of a vacuum pipe 12 for sucking up spent cleaning material which is guided to the axis of the head 10 by a squeegee member 13 in cooperation with brushes 14 mounted on the under surface of the head 10.

In my instant invention, the head has a driven ring-gear 15 fixedly mounted on an integral upwardly-extending hub 10^a which rotates on the vacuum pipe section 12^a as a fixed shaft. Said driven gear 15 is rotated from a drive gear 16 mounted on motor shaft 17 of motor 18. The motor and shaft are mounted endwise with the shaft in vertical position in an axially-disposed mounting aperture 19 in the gear-enclosing casing member 11. As illustrated, transmission shafts 20 and 21 are supported and mounted in said gear casing 11 in positions radially of and parallel to said axis; these shafts are provided with transmission gears 22—22^a and 23—23^a arranged in pairs, and the members of each pair of gears mesh, respectively, with said driven and drive gears 15 and 16, the casing 11 being provided with

suitable bearings 24—24^a and 25—25^a for the shafts 20—21.

Said gear-casing is open at its bottom to permit the extension thereinto of the hub 10^a and driven gear 15, and the circular base portion 26 of said casing abuts the top surface of the head 10 which is preferably provided with a metal bearing ring 27. The said casing is provided with suitable openings 28 to permit lubrication of the shafts 20 and gears 22 and is also provided with a cylindrical radial extension 29 adapted to support a horizontally-disposed section 12^a of said suction pipe 12, said extension 29 also being adapted to support an inwardly extending handle-tube 30 to which is connected and mounted by straps 31—31^a a cleaning-liquid-reservoir 32. The handle-pipe 30, as shown, is provided with a cross-bar handle 30^a and has for a part of its length mounted therein an upwardly-extending section 12^b of the suction pipe 12. Said upwardly-extending section 12^b is provided intermediate the ends of the tube 30 with a suitable connection member 33 to which is connected a vacuum hose 34 which extends to a portable vacuum tank 35 provided with a suitable cover 36. As illustrated in Fig. 3, the vacuum tank 35 is composed of metal and has mounted at its upper end and a cover 36 on which is mounted a conventional vacuum-producing element 37 comprising a motor 38 and fan 39 adapted to cause a suction inside the tank and through the hose 34 and suction pipe, connection 33 and suction pipe sections 12^b and 12^a, respectively, said section 12^a being extended as aforesaid through the head and the inlet 12^c of said pipe 12 being positioned closely adjacent to the surface to be cleaned and within the area bounded by the perimetric portions of the squeegee member 13.

Parts of said squeegee member 13 are suitably positioned, first, to surround and enclose cleaning material fed to the surface beneath the head, and thereafter to guide the spent cleaning material to the axis of the head and to an area adjacent to the entrance 12^c of the suction pipe or conduit 12, whereupon the suction means hereinabove described causes the material to be sucked up and passed to the tank 35 which is preferably provided with a suitably controlled air outlet 39^a. The cover is suitably fastened by swingable bolts 36^a mounted on the outer surface of the tank and having wing nuts at their upper ends adapted to engage the cover 36.

A suitable quantity of cleaning fluid is supplied to the tank 32 and this cleaning fluid is charged to the head through a circular channel 40 which, as shown, is mounted on the head outside the casing 11 and, as illustrated in Figs. 4, 5 and 7, the said channel is provided with a series of 60 vertical bores 41 extending downwardly from such channels 40 through the head to the bottom surface thereof. These bores are located adjacent to the perimeter to permit the material fed to such channels to reach the surface to be cleaned below the body portion 11^a of the head and within the area bounded by the squeegee 13 within which the brushes 14 operate.

An important feature of my invention comprises the provision on the bottom surface of the head of a special squeegee element 13 which is composed of a circular perimetric portion 13^a extending completely and continuously around the perimeter of the head and an inwardly-directed liquid-guiding portion 13^b connected at 75 its outer end to the perimetric portion, having

the concave face thereof extending in the direction of rotation of the head and being disposed in a spiral path which extends completely around the axis of the head and terminates at said axis in adjacency to the entrance 12^c of the axially located suction tube 12. Said inwardly directed portion provides a spiral-shaped continuous area between the outer surface thereof and the inner surface of the perimetric portion and also between inner and outer surfaces of turns and the brush 14, which is of similar spiral shape, is located within this area.

In the preferred embodiment of my invention, the brush 14 closely conforms to the shape of said area and is formed in a substantially spiral curve, has portions reduced in width at opposite ends and increased in width at the middle section thereof. Said brush begins at a point adjacent to the outer perimeter of the head and terminates at a point adjacent to the axis thereof in substantially parallelism to the inwardly-directed squeegee portion, and preferably will leave at opposite ends relatively small bare sections free of the brush.

In the embodiment shown, the brushes 14 are mounted upon a brush back 14^a and this brush back is releasably mounted on spring-projected and flanged connecting members 42 which pass through apertures 43 in the head and have spiral springs 44 arranged in a housing cavity in the head and adapted to resiliently press the brush-back outward and causing the brush-bristles to contact with a rug or other surface to be scrubbed.

In the preferred form of my invention, connecting members have flanges at opposite ends and the brush back 14^a of the brush is provided with keying slots 14^b into which the outer flange fits and which are closed in any suitable manner to retain the brushes firmly in position on the connecting members 42 to provide a resilient-mounting and a readily releasable connection of the brushes with the head.

In Figs. 1 to 6 of my invention, I have shown a squeegee of cylindrical cross-section which is preferably composed of a light metal, such as aluminum, and is particularly adapted for use in the shampooing of rugs.

In Fig. 7 I have illustrated in fragmentary section a squeegee 13^x which is formed of flat leather or other similar tough material, and is more especially adapted for cleaning flat surfaces composed of tile, concrete, wood or the like.

Having described my invention, I claim:

1. A portable surface cleaning or shampooing machine embodying, in combination, a mounting member, a head mounted to rotate in said mounting member, a squeegee element mounted on the bottom surface of said head and having rubbing contact with the surface to be cleaned, said squeegee element comprising a perimetric portion substantially encircling said head and a single inwardly-disposed portion of continuous, gradually winding spiral form extending outwardly in the direction of rotation from a point adjacent to the axis of rotation of the head to a point of merger with the perimetric portion, said gradually-winding portion of spiral form passing a plurality of times across a diametric line extending through said merger point and

said axis of rotation means for feeding a liquid cleaning material within said arcuate perimetric portion, said arcuate squeegee portion being adapted to retain and prevent the escape outwardly of cleaning material fed to a surface to be cleaned below and within the area bounded by said arcuate portion, and said inwardly disposed spiral portion being adapted to guide and deflect cleaning material used on said surface to a collection place at the axis of said head beneath the bottom surface thereof, a removal conduit at said axially-located collection place, and vacuum means for applying suction through such removal conduit to remove spent cleaning material at said axis.

2. A portable surface cleaning or shampooing machine embodying, in combination, a mounting member, a head mounted to rotate in said mounting member, a squeegee element mounted on the bottom surface of said head and having rubbing contact with the surface to be cleaned, said squeegee element comprising a perimetric portion substantially encircling said head and a single inwardly-disposed portion of continuous, gradually winding spiral form extending outwardly in the direction of rotation from a point adjacent to the axis of rotation of the head to a point of merger with the perimetric portion, said gradually-winding portion of spiral form passing a plurality of times across a diametric line extending through said merger point and said axis of rotation, means for feeding a liquid cleaning material within said arcuate perimetric portion, said arcuate squeegee portion being adapted to retain and prevent the escape outwardly of cleaning material fed to a surface to be cleaned below and within the area bounded by said arcuate portion, and said inwardly disposed spiral portion being adapted to guide and deflect cleaning material used on said surface to a collection place at the axis of said head beneath the bottom surface thereof, a brush of gradually-winding spiral conformation arranged on the head within the area bounded by said inwardly-disposed portion of said squeegee and also extending outwardly in the direction of rotation from a point adjacent to the axis of rotation of the head to the perimetric portion, a removal conduit at said axially-located collection place, and vacuum means for applying suction through such removal conduit to remove spent cleaning material at said axis.

EDWARD BERBERIAN.
